UNITED STATES PATENT OFFICE.

HENRY O. FLETCHER, OF BRIDGEPORT, CONNECTICUT.

SEARCHLIGHT APPARATUS.

1,418,553.

Specification of Letters Patent. Patented June 6, 1922.

Application filed October 20, 1919. Serial No. 331,895.

To all whom it may concern:

Be it known that I, HENRY O. FLETCHER, a citizen of the United States, residing at Bridgeport, in the county of Fairfield and 5 State of Connecticut, have invented certain new and useful Improvements in Searchlight Apparatus, of which the following is a specification, reference being had therein to the accompanying drawings.

10 While my invention is particularly adapted for use on vehicles, it may be employed in the various ways that search lights are used.

One object of my invention is to minimize the time necessary for operating the light, 15 thus affording the operator the opportunity to attend to various other duties.

The present invention is a modification of my pending application, Ser. No. 309,003, filed July 7, 1919, and differs mainly in the 20 means employed for lighting and extinguishing the lamp, also the construction is simplified and the switching mechanism included within the case, instead of being mounted on brackets as in the previous application.

25 The present invention provides means for lighting the lamp previous to turning the same, thus allowing the lamp to be lighted in straight-forward position. This is quite an advantage, inasmuch as the lamp may be lighted in any position, and may be used to illuminate the entire area included in its capacity.

30 The present invention also provides means for readily focusing the lamp within the reflector.

It also provides means for extinguishing the lamp automatically and causing the same to remain extinguished at all times when not 40 in use, thus minimizing the amount of current necessary to operate the lamp.

It also provides mechanism for automatically lighting the lamp when trained upon an object, relieving the operator of the care 45 and time necessary for this operation. It makes use of but a single switch, which simplifies construction and which functions to effectively light and extinguish the lamp without any unnecessary labor.

50 Other objects and advantages, combinations and details of construction will appear from a description of preferred embodiments of the invention shown in the accompanying drawings, in which,—

55 Fig. 1 is a rear elevation of one embodiment of the invention;

Fig. 2 is a vertical central cross-section of the same embodiment;

Fig. 3 is a rear elevation of another embodiment of the invention;

Fig. 4 is a vertical central cross-section of the form shown in Fig. 3; and

Fig. 5 is a diagrammatic view showing a preferred arrangement of the electric connections.

Referring to the drawings of Figs. 1 and 2, the yoke 1 is pivoted at 2 in bracket 3, and the lamp case 4 is pivoted at 5 and 6 in yoke 1. Pivot 2 shown in cross section in Fig. 2, consists of a pintle pin 7 carried by the yoke 1 and journaled within suitable bearings 8 and 9, spaced apart within a sleeve 10 fixed in bracket 3. Loosely mounted on pintle 7 between bearings 8 and 9 are collars 11 and 12. Collar 11 has an abutment 13 which engages abutment 14 on bearing 8, and also carries abutment 15 which engages with abutment 16 on pintle 7. On collar 12 is abutment 17 engaging abutment 18 on pintle 7 and this collar also carries 80 abutment 19 engaging abutment 20 on bearing 9. One end of torsional spring 21 engages collar 11, and the other engages collar 12 in such a manner as to force abutment 15 against abutment 16, and also to hold abutment 17 firmly against abutment 18. The abutment 14 on bearing 8 is in such position as to engage abutment 13 on collar 11, and abutment 20 on bearing 9 is in position to engage abutment 19 on collar 12, thus 85 normally holding the entire construction in equilibrium.

Within the sleeve 22 is a similar construction to that just described, which holds the lamp in equilibrium on pivots 5 and 6 in the 90 same manner as the previously described mechanism holds the yoke 1 in equilibrium in the bracket 3.

The electric lamp 23, having filament 23^a and reflector 24, may be of usual construction and will need no further description. The lamp 23 is inserted within sleeve 25, which is held in position by the split sleeve 25^a rigidly mounted on the reflector 24 and clamped by the yoke 26 and the clamp screw 100 27, thus holding it in the properly focused position. The contact springs 28 and 29 are mounted on insulations 30 and 31. The yoke 32 is pivotally mounted at 33 on sleeve 25, and the yoke 34 carrying the operating 105 lever, or handle 36 is pivotally mounted at 37 and 38 on yoke 32, thus allowing uni-

versal movement of operating handle 36. The plungers 39 are slidably mounted within cylindrical guides 40, and their movement limited thereby, and held lightly 5 against the operating handle 36 on four sides by compression springs 41, thus operating to hold it in position within the casing.

The contact ring 42 carried by and insulated from the casing is electrically connected to contact spring 28 by wire 43, and the contact disc 44 is carried by and insulated from the operating handle 36, and has direct connection through wire 45 to the battery or other electrical supply. The contact 10 spring 29 is connected through wire 46 also to the electrical supply.

It will be noticed that the outside diameter of contact disc 44 is slightly smaller than the inside diameter of contact ring 42, thus 20 serving to keep the electrical circuit open when operating handle 36 is in inoperative position. The compression springs 41 have much less tension than torsional springs 21, so that when the operating handle 36 is deflected in any direction from inoperative 25 position, the first action is to compress one or more of springs 41, causing the contact disc 44 to make electrical contact with contact ring 42, thus completing the circuit and 30 lighting the lamp.

It will be noticed that by this action the lamp is lighted before it is turned in any direction, and the rays directed straight ahead. If additional pressure is added to 35 the operating handle 36 to the right or to the left, the yoke 1 is turned on pintle 2, thus overcoming the tension of the torsional spring 21 and the rays of the light deflected accordingly.

40 If sufficient pressure is exerted to the operating handle 36 in an upward or downward direction, the lamp is lighted and turned on pintles 5 and 6, and the rays directed upward or downward. If pressure is applied to the operating handle 36 in an 45 angular direction, the yoke 1 is turned on pintle 7 and the lamp 4 is also turned on pintles 5 and 6, thus deflecting the rays of the lamp accordingly.

50 It will be seen by this arrangement that the lamp will be lighted if pressure is applied to the operating handle 36 in any direction, and also if sufficient pressure is applied to operating handle 36 the lamp may 55 be turned in any direction.

Upon relieving the pressure of the operating handle 36 the plungers 39 immediately return the operating handle to inoperative position in the housing by reason of the action of the springs 41, thus breaking the contact between contact disc 44 and contact ring 42, opening the circuit and extinguishing the lamp, and the lamp immediately is returned to normal position by reason of the action 65 of the torsional springs within sleeves 10

and 22, and held by abutments as above described. If it is desired to adjust the lamp 70 23 in focusing position in reflector 24, the clamp screw 27 is loosened, releasing the pressure on the clamp yoke 26, which allows the sleeve 25 and the lamp 23 to slide within split sleeve 25^a by movement which may be imparted from operating handle 36, and the clamp screw 27 may be then tightened, which holds the lamp 23 firmly in place. 75

Referring to Figs. 3 and 4, yoke 46^a is pivoted at 47 in bracket 48, and the lamp casing 49 is pivoted at 50 and 51 in yoke 46^a. The operating handle 52 is universally mounted on pivots 53 and 54 carried by the bracket 80 55 fast on the case 49. The flat springs 56 press against handle 52 on four sides. The stops 57 limit the movement of springs 56, thus holding the handle 52 in inoperative 85 position. The contact disc 58, mounted on 89 and insulated from the operating handle 52, is connected to the electrical supply; and the contact ring 59, mounted on and insulated from the case 49, is electrically connected to contact pin 59^a. The contact pin 60 is also 90 connected to the source of electrical supply.

It will thus be seen that if the operating handle 52 is deflected in any direction, the contact disc 58 will make electric contact with contact ring 59, thus completing the 95 circuit and lighting the lamp 61.

Extending from the bracket 48 is an arm 62, to which one end of the cable 63 is connected, the other end being connected at 64 to grooved pulley 65. The pulley 65 is 100 loosely mounted on pivot 66. One end of torsional spring 67 is attached to pivot 66, the other end being connected to the pulley 65. When the lamp is turned in any direction from the position shown, the cable 63 is 105 caused to pay out through the opening 68 in the case 49, and thus unwinding from the pulley 65 causing it to revolve and wind up the spring 67. Upon releasing the pressure 110 upon the lamp the tension of the spring 67 causes the pulley 65 to rewind the cable 63 and return the lamp again to its normal position.

The tensions exerted by torsional spring 67 and flat springs 56 are such that the flat 115 springs 56 will be operated to make electric contact before the torsional spring 67 acts to allow the lamp to be turned from its normal position, thus causing the lamp to be lighted before it is turned. Upon releasing the pressure of operating handle 52, it will be noticed that the lamp immediately returns to normal position, and is automatically extinguished, without any exertion or thought on the part of the operator. Referring to Figs. 120 1 and 2, the lever 68 is pivoted at 69 on the lamp case 4 and may be swung downward so that the cam-shaped surface 70 will deflect the operating handle 36, and hold the contact disc 44 against contact ring 42 thus 125 130

maintaining the switch closed and the lamp lighted.

The switch actuating mechanism may be employed without the lamp returning means to advantage if desired, the usual frictional resistance to the turning of the lamp causing the switch operating element to first actuate the switch and then turn the lamp in the same manner as when springs for returning the lamp to a central position are employed.

From the foregoing, it will be noticed that many changes of detail and combinations of construction may be resorted to without departing from the spirit and scope of my invention.

Having thus described preferred embodiments of my invention, what I claim as new and desire to secure by Letters Patent of the United States is:—

20 1. In an apparatus of the kind described, a movable lamp, means for resisting the movement of said lamp, a lamp moving member movable relative to said lamp, means of different strength than said resisting means for resisting such relative movement, and lamp lighting means actuatable by said member.

25 2. In combination, a universally movable lamp, a lighting switch for said lamp, and a member mounted for universal movement relative to said lamp and actuatable through a continuous movement in any direction serially to actuate said switch and move said lamp.

30 3. In combination, a turnable lamp, means for lighting and extinguishing said lamp, and means actuatable by a continuous movement to actuate said first means to light and then to turn said lamp.

35 4. In combination, a turnable lamp, means to light and extinguish said lamp, and a lever for turning said lamp fulcrumed on said lamp and movable relative thereto to actuate said means.

40 5. In combination, a turnable lamp, a lever for turning said lamp fulcrumed on said lamp, a switch contact movable with said lever, a cooperating switch contact fixed to said lamp, and a lighting circuit controlled by said contacts.

45 6. In combination, a universally turnable lamp, a lever for turning said lamp universally fulcrumed on said lamp, a switch contact controlled by said lever, a cooperating switch contact carried by said lamp and engageable by said first contact on movement of said lever in any direction from one position relative to said lamp, and means tending to retain said lever in said one position.

50 7. In combination, a universally turnable lamp, a lever for turning said lamp universally fulcrumed on said lamp, a switch contact controlled by said lever, a coop-

erating switch contact carried by said lamp and engageable by said first contact on movement of said lever in any direction from one position relative to said lamp, means tending to retain said lever in said one position, and means tending to retain said lamp in a definite position.

55 8. In combination, a universally turnable lamp, a lever for turning said lamp universally fulcrumed on said lamp, a switch contact controlled by said lever, a cooperating switch contact carried by said lamp and engageable by said first contact on movement of said lever in any direction from one position relative to said lamp, means tending to retain said lever in said one position, and means for holding said lever in position to engage said contacts.

60 9. In combination, a lamp having a reflector and a light source movable relative to said reflector, means for lighting and extinguishing said lamp, and a lever rockable on its fulcrum to actuate said means and actuatable to move said light source relative to said reflector.

65 10. In combination, a movable lamp having a reflector and a light source movable relative to said reflector, means for lighting and extinguishing said lamp, and a lamp moving lever fulcrumed on said lamp and controlling said means by moving about said fulcrum and also movable to adjust said light source relative to said reflector.

70 11. In combination, a lamp having a reflector and a light source movable relative to said reflector, means for lighting and extinguishing said lamp, a lever movable about its fulcrum to control said means and connected to said light source and operable to move said source relative to said reflector, and means for holding said source fixed relative to said reflector.

75 12. In combination, a turnable lamp, a lighting switch for said lamp, and a lamp turning and switch actuating member having a lost motion connection to said lamp constructed and arranged to actuate said switch during the taking up of the lost motion.

80 13. In combination, a pivoted lamp, a member movable on said lamp for lighting and extinguishing said lamp and for moving said lamp, and means normally holding said member in lamp extinguishing position.

85 14. In combination, a pivoted lamp, a member movable on said lamp for lighting and extinguishing said lamp, returning means normally holding said member in lamp extinguishing position, and means for rendering inoperative said returning means.

90 In testimony whereof, I have signed my name to this specification.

HENRY O. FLETCHER.
